His Attorney.

UNITED STATES PATENT OFFICE.

FRANCIS J. BULLIVANT, OF ST. LOUIS, MISSOURI, ASSIGNOR TO VALLEY ELECTRIC COMPANY, OF ST. LOUIS, MISSOURI, A CORPORATION OF MISSOURI.

SHORT-CIRCUITING DEVICE.

Application filed November 5, 1925. Serial No. 67,111.

This invention pertains to a commutator short-circuiting devices such as are used on alternating current commutator motors.

One of the objects of this invention is to provide a short-circuiting device which will be positive in its operation and accurate in its setting.

Another object of this invention is to provide such a device in which the centrifugal force of the contactors is effective in operating the device and in which a positive and sudden action of the contactors is insured.

Another object is to provide such a device which shall be cheap to manufacture and simple to assemble.

Further objects will appear from the following description taken in connection with the accompanying drawing in which

Figure 1 is a fragmentary sectional view of 20 an armature with a short circuiting device embodying this invention:

Figure 2 is a similar view somewhat enlarged showing the contactors in operative position.

Referring now to the accompanying drawing 1 designates the armature shaft upon which may be mounted one or more flanges 2 to support the laminæ 3. A commutator hub 4 mounted on the flange 2 supports the commutator segments 5 in any usual and approved manner. All of this construction may be of any suitable type well known in the art.

Mounted on the shaft 1 and within the commutator hub 4 is a metal cup 6 formed of sheet metal and provided with a central cylindrical neck adapted to fit the shaft 1 and an outer flange 7 providing between it and the central neck an annular recess adapted to receive the contactors as will presently be described. A series of contactors 8, which may be formed by punching out of copper or other suitable material, is provided for short circuiting the commutator. Each contactor is formed with a hooked shaped rear end 9 and a weighted front end 10. The weighted end 10 is also provided with a contacting lug 11 on its outer edge. The hooked ends of the contactors are adapted to seat in the annular recess formed in the cup 6 which thus provides a support for the entire series of contactors. At spaced points in the bottom of the cup 6, spacers 12 are formed by punching the same from the bottom cup and bending inwardly as shown in Figure 2. These spacers

extend between the contactors 10 at certain points and serve to maintain said contactors in proper spaced relation and to drive the same when the armature rotates, and prevent sidewise tipping of the contactors so as to prevent their disengagement. These spacers are slotted to receive the rim 15 hereinafter described.

Mounted on the supporting cup 6 is a retainer 13 having a reduced cylindrical portion 14 adapted to fit over the central neck of the support 6 so as to be slidable thereon and having an outwardly flared rim 15 at the rear end thereof. The flared rim 15 is adapted to fit into the hooked ends 9 of the assembled series of contactors as illustrated in Figure 2. The retainer 13 is also provided just inside of the rim 15 with a conical cam portion 16 for a purpose which will be described later.

In assembling this device the contactors are all assembled on the retainer 13 by placing the hooked ends 19 over the rim 15 of the retainer. When a complete set of contactors has been assembled, the cup 6 is placed over the ends of the contactors, the central neck entering part 14 of the retainer. The contactors are now securely held in assembled relation by the co-operation of the cup 6 and the retainer 13. After assembly the retainer is secured to the support by bending outwardly from the support lugs 17 to extend into openings 18 in the retainer so as to lock these parts together, but at the same time permit a limited movement of the retainer on the support. The assembled device may then be slipped on the shaft after which a washer 19 of fibre or any suitable insulating material is placed over the end of the retainer 13 and so as to close the opening in the commutator 5. A governor spring 20 is then slipped over the shaft and against the washer 19 and compressed. A flanged washer 21 is then slipped over the shaft and against the spring. A split collar 22 is now inserted in an annular groove 23 in the shaft, after which the washer 21 may be released so as to cover and retain the collar 22. This serves to lock the entire device in place on the shaft.

In the operation of this device, the spring 20 presses rearwardly upon the retainer 13 which engages the hooked ends 9 of the contactors at its cam portion 16. The contactors in turn engage the curved rim 24 of the flange 7 at a cam portion 25 on each contactor. The

pressure of the retainer on the ends of the contactors causes the contactors to pivot at 25 so as to retract said contactors radially inwardly and prevent the same from contacting with the segments 5. This is the position of the device when the armature is at a standstill. As the motor starts the centrifugal force of the weighted ends 10 of the contactors causes the same to tend to move outwardly 10 against the tension of the spring 20. This tendency increases as the speed increases. At a certain pre-determined speed the centrifugal force of the contactors will be sufficient to overcome the spring pressure, 15 whereupon the contactors will move outwardly into contact with the commutator segments. During such movement the contactors pivot at 25 on the support with a sliding movement over the rim 24. At the same time, 20 the hooked ends 9 move outwardly along the cam portion 16 of the retainer, thereby forcing the retainer to move along the support against the pressure of the spring 20. It will be noted that on account of the moving pivot 25 at 25, and also on account of the cam action at 16, the radial movement of the outer end 10 of the contactor is quite large as compared with the movement of the retainer while compressing the spring. Accordingly, since the 30 spring compression is slight, the difference in spring tension in its outer and inner positions will be slight. At the same time, on account of the considerable radial displacement of the weighted end of the contactor, 35 the difference in its centrifugal force between its inner and the outer positions will be comparatively great. Consequently, the action of the contactors will be positive and at the pre-determined speed they will move outwardly with a sharp snap. This is a very advantageous feature since it results in a very sudden making or breaking of the contact at the commutator so that comparatively little burning of the contacts can take place. It 40 will be seen, furthermore, that the moving pivot at 25 is of material assistance in bringing about this effect. It will be seen, therefore, that in accordance with this invention a short circuiting device is provided which 45 is positive in its action so that it makes contact with a sharp snap. This device furthermore, is very compact and of such simple construction as to be cheaply manufactured and easily and quickly assembled.

50 It is obvious that various changes may be made in details of construction without departing from the spirit of this invention; it is, therefore, understood that the invention is not to be limited to the specific details 55 shown and described.

Having thus described the invention, what is claimed is:

60 1. A commutator short-circuiting device, comprising, a support, a series of centrifugally operable contactors thereon, a part on said

support adapted to provide a moving pivot bearing for said contactors, a retainer movable on said support and engaging said contactors to retain the same in inoperative position, means for tensioning said retainer, and 70 means for interlocking said retainer with said support.

65 2. A commutator short-circuiting device, comprising, a support, a series of centrifugally operable contactors thereon, a part on said support adapted to provide a moving pivot bearing for said contactors, said support having an annular recess and said contactors having hooked ends nested in said recess, a retainer movably mounted on said support 80 and having a cam portion engaging said hooked ends to retain said contactors in inoperative position, and means for tensioning said retainer.

75 3. A commutator short-circuiting device, comprising, a support, a series of centrifugally operable contactors thereon, a part on said support adapted to provide a moving pivot bearing for said contactors, said support having an annular recess and said contactors having hooked ends nested in said recess, a retainer movably mounted on said support and having a flared rim providing a cam portion 90 engaging said hooked ends to retain said contactors in inoperative position, and means 95 for tensioning said retainer.

80 4. A commutator short-circuiting device, comprising, a support, a series of centrifugally operable contactors thereon, a part on said support adapted to provide a moving pivot bearing for said contactors, said support having an annular recess and said contactors having hooked ends nested in said recess, a retainer movably mounted on said support and having a cam surface engaging said hooked 100 ends to retain said contactors in inoperative position, and means for tensioning said retainer, whereby the centrifugal force of said contactors operates through said cam surface 105 to move said retainer.

85 5. In an electric motor having a rotor provided with a commutator, a hollow commutator support adapted to support the commutator with the inner faces of its segments exposed, a contactor support within said commutator support and having an annular socket the outer edge of which is adapted to provide a pivot bearing, a series of contactors having hooked ends nested in said socket, pivot portions engaging said bearing and 110 portions adapted to contact with the inner faces of the segments, and a retainer having a cam portion yieldingly engaging said hooked ends to retract said contactors from the commutator.

90 6. In an electric motor having a rotor provided with a commutator, a hollow commutator support adapted to support the commutator with the inner faces of its segments exposed, a contactor support within said com- 115

mutator support and having an annular socket the outer edge of which is adapted to provide a pivot bearing, a series of contactors having hooked ends nested in said socket, 5 pivot portions engaging said bearing and portions adapted to contact with the inner faces of the segments, and a retainer interlocked with said contactor support having a cam portion yieldingly engaging said hooked 10 ends to retract said contactors from the commutator.

7. In an electric motor having a commutator, an assembled unit comprising, a contactor support having an annular socket the 15 outer edge of which is adapted to provide a pivot bearing, a series of contactors having hooked ends nested in said socket and pivot portions engaging said bearing, and a retainer engaging said hooked ends and interlocked with said support. 20

8. In an electric motor having a commutator, an assembled unit comprising, a contactor support having an annular socket the outer edge of which is adapted to provide a pivot 25 bearing, a series of contactors having hooked

ends nested in said socket and pivot portions engaging said bearing, and a retainer having a cam portion engaging said hooked ends and interlocked with said support. 30

9. In an electric motor having a rotor provided with a commutator, a hollow commutator support adapted to support the commutator with the inner faces of its segments exposed, a contactor support within said commutator support and having an annular 35 socket the outer edge of which is adapted to provide a pivot bearing, a series of contactors having hooked ends nested in said socket, pivot portions engaging said bearing and portions adapted to contact with the inner 40 faces of the segments, a retainer having a cam portion yieldingly engaging said hooked ends to retract said contactors from the commutator, and a disc closing the bore of the commutator and bearing yieldingly against said 45 retainer.

In testimony whereof I affix my signature this 4th day of Sept., 1925.

FRANCIS J. BULLIVANT.
